UNITED STATES PATENT OFFICE.

GEORGE R. RICH, OF OAK PARK, ILLINOIS, ASSIGNOR TO RICH TOOL COMPANY, OF CHICAGO, ILLINOIS, A CORPORATION OF ILLINOIS.

METHOD OF PRODUCING PUPPET-VALVES FOR INTERNAL-COMBUSTION ENGINES.

1,100,779.

Specification of Letters Patent.

Patented June 23, 1914.

Application filed October 14, 1912. Serial No. 725,621.

To all whom it may concern:

Be it known that I, GEORGE R. RICH, a citizen of the United States, residing at Oak Park, in the county of Cook and State of Illinois, have invented a new and useful Improvement in Methods of Producing Puppet-Valves for Internal-Combustion Engines, of which the following is a specification.

10 This invention relates to puppet valves for internal combustion engines and the method of producing such valves. It is well known to those skilled in the art in which this invention belongs, that the puppet valves of internal combustion engines are subjected, when in use, to very high degrees of temperature, that there is constant danger of such valves warping by reason of the high temperature and that the bearing 15 surfaces of the valves become pitted and accumulate carbon, so that in a short time they must be reground and the carbon removed in order that they may give the best service.

The main objects of this invention are to 20 increase the efficiency of puppet valves of this class, to produce a puppet valve which is not injuriously affected by the high temperature of the gases in internal combustion engines, to produce one which will not warp 25 when subjected to such high temperatures, and one whose bearing surface will not pit and accumulate any appreciable amount of carbon.

The invention consists in the method of 30 producing such a valve by subjecting a heated bar of "tungsten" steel to comparatively light hammer strokes in a particular manner, as will be more fully set forth in this specification and definitely pointed out 35 in the claims.

A drawing is furnished herewith for use 40 in illustrating the method employed in producing the valve and in said drawing, Figure 1 is a side elevation of a hammer, employed in the method of producing the 45 valve, Fig. 2 is a side elevation of a fragment of a second hammer, showing in vertical section, a pair of dies used in the second operation of the method, Fig. 3 is a side view 50 of a fragment of a rod of "tungsten" steel, Fig. 4 is a side elevation of the valve body after the first operation, Fig. 5 is a side elevation of the completed valve body and Fig. 55 6 is an end view thereof.

55 Referring to said drawing, the puppet

valve, forming my present invention, comprises a disk like valve piece, 10, forming the puppet valve proper, and having an annular bearing face, 11, usually tapered in form and adapted to seat upon a suitable 60 valve seat. A valve stem, 12, projects from one face of the valve, and the valve and its stem are made of one piece of metal, containing in its composition a suitable percentage of "tungsten," at least six per 65 cent, "tungsten," although better results may be had by employing a higher percentage of "tungsten." By reason of the peculiar method employed in the production of this valve, the grain of the metal is very 70 fine throughout, it having been treated, in the method of production, in such a manner that throughout its entirety the metal is compacted. "Tungsten" steel is hard, does not lose its hardness and warp even when 75 subjected to temperatures reaching as high as 1200 degrees Fahrenheit, and the bearing face of a valve, made of "tungsten" steel, does not pit, nor does it collect any appreciable amount of carbon when used in an 80 internal combustion engine, and is subjected to the high temperatured gases therein.

In carrying out my method of producing "tungsten" steel puppet valve bodies, a rod or block, A, of "tungsten" steel, or steel 85 containing a percentage of "tungsten," and of about one half the diameter of the finished valve, is first heated to a temperature of about 2300 degrees Fahrenheit, and thereupon a portion, A¹, of its length is subjected to comparatively light blows of a hammer, described below, whereby said portion is compressed and lengthened out to substantially the diameter and length of the finished valve stem, after which the large 90 end, A², is subjected to comparatively light hammer strokes, in an endwise direction of the stem, and flattened down into the rough form of a puppet valve body.

In producing a valve in accordance with 100 this method, a power operated hammer, 15, is employed, having an anvil, 16, and a hammerhead, 17, on a long arm, 18, fulcrumed at one end to a standard, 18^a. Dies, 19, 20, are carried by the anvil and hammerhead, respectively, and said dies are formed with a plurality of opposing curved grooves, 21, 21^a; and said grooves in their order of arrangement, are of gradually decreasing diameters, the largest groove being somewhat 110

smaller than the diameter of the original rod, whereas the smallest groove is a trifle larger than the diameter of the finished valve stem. The same hammer or a second 5 hammer, 15^a, is provided with a die, 22, rotatively mounted in the anvil, 16^a, of the hammer, and having a central vertical hole of substantially the diameter of the valve stem of the puppet valve, said hole being 10 flared at its upper end as seen at 23. To the hammerhead, is secured a die, 24, having a concave face, 25, registering with the opening in the die, 22.

In my method of producing a "tungsten" 15 steel valve, the heated rod, A, is first placed in the largest groove in the die, 19, (with enough metal projecting beyond the groove to form the head) and then subjected to a large number of comparatively light blows 20 of the die carried by the hammerhead, whereby said portion of the rod is compressed and lengthened out. The reduced portion is then subjected to the blows of the hammer, while lying in the other grooves, 25 one after another, until that portion of the rod is reduced to substantially the desired diameter and length of the valve stem. Thereafter the piece is reheated to the required temperature, the stem inserted in the 30 hole of the die, 22, and the protruding portion, A², subjected to comparatively light hammer strokes of the hammer, containing the flattening die, 24, until that protruding portion has been flattened down into the 35 rough form of the valve, care being taken to rotate the lower die, 22, frequently so that the metal may be spread evenly throughout the body of the valve.

With the use of a fulcrumed hammer, the 40 metal in the valve proper, is forced toward one side of the valve, and by rotating the die, between the hammer strokes, the metal may be spread evenly in all directions throughout the body of the valve. After the rough 45 piece has been completed it is annealed, finished, and rehardened.

It is obvious that a "tungsten" steel valve 50 constructed in accordance with the above described method, comprises an extremely solidified mass of "tungsten" steel which, on account of its peculiar characteristics, effectively resists the action of the high temperatures of the gases of internal combustion engines, does not warp, nor does its bearing 55 face pit and accumulate any appreciable

amount of carbon. A valve and its stem, made by cutting it out of a bar of "tungsten" steel, will not accomplish this result because it will be found that the core or center of a bar of steel, of large enough diameter to make the valve therefrom, is not as dense as the surface material, and therefore capable of resisting the high temperatures, as is the surface material of such a rod. A "tungsten" steel puppet valve, such 60 as may be constructed in accordance with the present method, is illustrated, described, and claimed in my co-pending application, Serial No. 703,202, filed June 12, 1912, and allowed November 20, 1912. 70

I claim as new and desire to secure by Letters Patent:

1. The herein described method of producing "tungsten" steel puppet valve bodies, which consists in subjecting the greater portion of a highly heated rod of "tungsten" steel, of less diameter than the diameter of the finished valve, to comparatively light strokes of a hammer, in a direction transverse of the rod, and thereafter subjecting 75 the other portion to comparatively light strokes of a hammer in an endwise direction, whereby said latter portion is flattened out in the form of a puppet valve integral with its stem. 80

2. The herein described method of producing tungsten steel puppet valve bodies, which consists (1) in subjecting a portion of a highly-heated rod of tungsten steel, of less diameter than the diameter of the finished 90 valve, to comparatively light strokes of a hammer, in a direction transverse of the rod, and (2) thereafter subjecting the other portion of said rod to comparatively light 95 strokes of a hammer in an endwise direction and (3) turning said rod while so subjecting it to said blows in an endwise direction, whereby the unreduced end of the rod is 100 symmetrically flattened out into the form of a puppet valve head integral with its stem.

In testimony whereof I have hereunto set my hand at Chicago, Cook county, Illinois, this 9th day of Oct. 1912, in the presence of two witnesses.

GEORGE R. RICH.
